UNITED STATES PATENT OFFICE.

THOMAS NATHAN RUSSELL, OF CHICAGO, ILLINOIS, ASSIGNOR TO CHICAGO-CLEVELAND CAR ROOFING COMPANY, OF CHICAGO, ILLINOIS, A CORPORATION OF ILLINOIS.

CAR-ROOF.

1,340,685.

Specification of Letters Patent.

Patented May 18, 1920.

Application filed July 25, 1918. Serial No. 246,632.

To all whom it may concern:

Be it known that I, THOMAS NATHAN RUSSELL, a citizen of the United States, residing in Chicago, in the county of Cook and 5 State of Illinois, have invented a new and useful Improvement in Car-Roofs, of which the following is a specification.

My invention relates to car-roofs of the "outside metal type" and has for an object 10 the providing of an outside metal roof construction in which the roof-sheets shall be retained along their ridge-ends by a cap that makes interlocking engagement with them and yet permits them freedom of bodily 15 movement; and the invention has for other objects such other advantages and results as may be found to obtain in the structures hereinafter set forth and claimed.

In the accompanying drawings, forming 20 part of this specification, and showing for purposes of illustration a preferred embodiment of the subject matter hereinafter claimed,

Figure 1 is a top plan view of a car-roof 25 exemplifying my invention:

Fig. 2 is a section on the line 2—2 of Fig. 1;

Fig. 3 is an enlarged detailed section of 30 the ridge construction on the line 3—3 of Fig. 1;

Fig. 4 is an enlarged detailed section of the eaves construction on the line 4—4 of Fig. 1;

Fig. 5 is an enlarged plan view of the cap- 35 ping arrangement and construction along the ridge of the roof;

Fig. 6 is a detailed section on the line 6—6 of Fig. 1;

Fig. 7 is a side elevation of the eaves portion 40 of the roof;

Fig. 8 is a plan view of the eaves portion of the roof;

Fig. 9 is a perspective view of the roof-sheets and ridge-caps and corner-caps, to 45 show the manner of their relative arrangement along the ridge of the roof, the several members being separated to expose the ridge construction more clearly;

Fig. 10 is a perspective view of one of the 50 mullion-caps that overlie the mullions and engage the roof-sheets laterally;

Fig. 11 is a perspective view of a pair of 55 mullions in place on the roof-sheathing near the ridge of the roof; and

Fig. 12 is another detailed section of the

eaves construction similar to the view given in Fig. 4 but showing a modified form adapted to a roof-frame in which there is a wooden side-plate instead of the angle side-plate shown in Fig. 4.

60

Like reference numerals indicate like parts in all the drawings.

20, 20 are the roof-sheets, each of which has an under-bent hooked flange 21 along its eaves-end and an upstanding inwardly rebent flange 22 along each of its sides, and has along its ridge-end a flange 23 that is upwardly bent and inwardly rebent and shouldered, the free edge 24 of the shouldered portion 25 extending inward over the body of the sheet. These roof-sheets are disposed in pairs on opposite sides of the ridge of the roof and occupy the spaces between the transverse mullions 26 that are nailed on the top of the wooden roof-sheathing 27 at intervals along the roof; the intervals between the successive mullions being somewhat greater than the overall width of the said roof-sheets that occupy the spaces between these mullions, so that each roof-sheet has some free-space for movement laterally between the mullions on either side of it. Along the ridge, between the mullions, there are ridge-caps 28 that are of inverted channel form with outwardly extending and 70 inwardly rebent flanges 29 along each edge of the channel 30. The channel 30 of said ridge-caps overlies and engages the faces of the aforesaid shoulders 25, and the rebent edge-flanges 29, of the ridge-caps, are 75 hooked freely over the aforesaid extended free edges 24 of the shouldered portion of the roof-sheet flanging. This manner of interlocking and engagement of the ridge-cap with the ridge-flanges of the roof-sheets retains the roof-sheets from displacement 80 from the eaves of the roof and yet permits them freedom of movement both laterally and toward the ridge-line of the roof. Additionally to secure the roof-sheets from any possible disengagement from their interlocking with the ridge-caps, a lock-strip 31—a simple, loose strip of wood—may be slipped in under the ridge-cap and between the ridge-flanges of the roof-sheets before the 85 ridge-caps are finally secured in position.

The ends of the ridge-caps are secured in position by the corner-caps 32, which are doubly shouldered to conform with and fit over the outside of the ridge-cap ends and 90

95

100

105

110

are also recessed to fit over the adjacent ends of the seam-caps 33 that cap the mullions. These seam-caps or mullion-caps have depending lateral flanges that considerably 5 overhang the sides of the mullions and are inwardly rebent so that they may be telescoped into and loosely engage with the aforesaid upstanding side-flanges 22 of the roof-sheets, allowing free movement of said 10 roof-sheets toward and away from the mullions. The eaves-ends of the mullions overhang the recess 27 that is rabbeted out along the top of the eaves portion of the roof-sheathing; and the eaves-end 34 of each 15 mullion cap is bent downward and rebent inward to cover the eaves-ends of the engagement between the mullion-cap flanges and roof-sheet flanges and to hook under and engage the said overhanging eaves-end 20 of the mullion. The mullion-caps are secured near the ridge by the nails 35 that are driven through the mullions, mullion-caps and roof-sheathing and into wooden ridge-pole sections 36 that span the space 25 from carline to carline and are secured by the underneath ridge-plate 37 that extends under all the carlines. The running-board saddles 38 rest on top of the corner-caps 32 and the mullions and their caps, and each 30 saddle is secured by the bolt 39 passing down through it and through the corner-cap, mullions, sheathing, ridge-pole and underneath ridge-plate 37. Over the top of the bolt 39 a small water-proofing metal cap 35 is let into the recess in the top of the running-board saddle to prevent seepage of water into the bolt-hole. It may be noted 40 that the carlines are fewer in number than the mullion-divided spaces along the top of the roof, and therefore do not directly underlie the mullions, with the possible exception of the carline at the middle of the 45 length of the roof. Each carline 41 is U-shaped and extends from side to side of the car, and in its channel there is a wooden filler; and so where the carline underlies the mullions at the middle of the length of the car the before-mentioned nails 35 would 50 enter the said wooden filler of the carline and the said bolt 39 would pass through such wooden filler and the bottom of the channel of the carline and then through the underneath ridge-plate 37.

The rebent eaves-flanges 21 of the roof-sheets are loosely engaged by the hook-strips 42 that occupy the aforesaid recess along the eaves portion of the roof-sheathing and are secured well within the eaves edge of said sheathing. These hook-strips 60 extend along the entire length of the said eaves-recess and are made in sections that lap end for end. Overlying the under portion of these hook-strips and extending in between said portion and the rebent roof-sheets 65 sheet flange 21 that is engaged under the

upper portion of the hook-strips there is an eaves-flashing 43, the inner end of which is flanged diagonally upward, at 44, and the outer portion of which is bent downward over the outside of the car and has 70 its lower edge flaring outward somewhat to deflect drip water. In the form of structure shown in Figs. 1 to 11, the said hook-strips 42 and flashings 43 are secured by the short bolts 45 positioned under each overhanging mullion-end and extending down through the outwardly projecting upper member of the metallic angle side-plate 46. And in the modified form of structure shown in Fig. 12 the hook-strips are secured by the nails 47 driven through the hook-strip and roof-sheathing and into the wooden side-plate 48, and the flashings are secured in their depending portion by the nails 49 driven through the side-sheathing 80 50 and into the said wooden side-plate.

From the foregoing description and from inspection of the drawings, it will be noted that the roof-sheets are freely floating, being free to shift bodily in all directions, 90 and yet have all of their edges locked from displacement, each edge being provided with a flange that interlocks freely within a reversely formed flange of an adjacent roof-member. Such interlocking is effected with 95 the hook-strips along the eaves-ends of the roof-sheets, and with the flanged mullion-caps along their sides, and with the ridge-caps along their ridge-ends. The entire sheet, although locked from displacement, 100 has essential freedom of movement bodily from side to side between the mullions and toward and away from the ridge-line and eaves of the roof of the car; and yet the ridge-caps, engaging the shoulders of the 105 ridge-end flanges of the roof-sheets, prevent the sheets from being displaced too far toward the eaves of the roof. It will further be noted that the retaining means along the eaves-ends of the roof-sheets and such eaves-ends of the sheets themselves are secured 110 well within the eaves-edge of the roof, and nothing overhangs said edge except the eaves-flashings that are independent of both the roof-sheets and their retaining hook-strips so that a side-wiping accident that may damage or rip away these eaves-flashings will neither damage nor detach either 115 the roof-sheets or their retaining hook-strips. Other advantages will be apparent 120 from the description and drawings.

The invention may be embodied in forms of construction other than the specific form that has been shown and described for purposes of illustration, and still be within the 125 scope and subject matter of the claims hereinafter made.

I claim:

1. In a metal car-roof, in combination: roof-sheets disposed on opposite sides of the 130

- ridge of the roof and each having along its ridge-end a flange that is upwardly bent and inwardly rebent and shouldered, the free edge of the shouldered portion extending inward over the body of the sheet; and a ridge-cap of inverted channel form with outwardly extending and inwardly rebent flanges along each edge of the channel, the channel being adapted to overlie and engage the faces of the aforesaid shoulders of the roof-sheet flanging, and the rebent edge-flanges of the channel being hooked freely over the aforesaid extended free edges of the roof-sheet flanging; whereby the ridge-cap retains the opposite roof-sheets from displacement toward the eaves of the roof and at the same time forms with the roof-sheet flanging an interlocking connection that permits free shifting of the sheets toward the ridge of the roof; substantially as specified.
2. In a metal car-roof, in combination: freely floating roof-sheets flanged along all of their four edges and having each of the flanges formed to interlock freely within a reversely formed flange of an adjacent roof-member, the entire body of the sheet being free of other engagement with the roof structure; and said adjacent roof-members provided with such reversely formed flanges; whereby the roof-sheets are free to shift bodily in all directions and at the same time have all of their edges locked from displacement; substantially as specified.
3. In a metal car-roof, in combination: roof-sheets disposed on opposite sides of the ridge of the roof and each having along its ridge-end a flange that is upwardly bent and inwardly rebent and shouldered, the free edge of the shouldered portion extending inward over the body of the sheet; a ridge-cap of inverted channel form with outwardly extending and inwardly rebent flanges along each edge of the channel, the channel being adapted to overlie and engage the faces of the aforesaid shoulders of the roof-sheet flanging, and the rebent edge-flanges of the channel being hooked freely over the aforesaid extended free edges of the roof-sheet flanging; seam-caps extending transversely of the roof and freely engaging the sides of the roof-sheets; and corner-caps shouldered over the mutually adjacent ends of the ridge-caps and seam-caps, to hold the ridge-caps and seam-caps in place at the ridge of the roof; substantially as specified.
4. In a car-roof, in combination: roof-sheathing: mullions secured at intervals transversely along the top of said sheathing; roof-sheets occupying the spaces between said mullions, on opposite sides of the ridge of the roof, each of said roof-sheets having along its ridge-end a flange that is upwardly bent and inwardly rebent and shouldered, the free edge of the shouldered portion extending inward over the body of the sheet; a ridge-cap of inverted channel form with outwardly extending and inwardly rebent flanges along each edge of the channel, the channel being adapted to overlie and engage the faces of the aforesaid shoulders of the roof-sheet flanging, and the rebent edge-flanges of the channel being hooked freely over the aforesaid extended free edges of the roof-sheet flanging; whereby the ridge-cap retains the opposite roof-sheets from displacement toward the eaves of the roof and at the same time forms with the roof-sheet flanging an interlocking connection that permits free shifting of the sheets toward the ridge of the roof; substantially as specified.
5. In an outside metal car-roof, a metal roof-sheet having along its ridge-end a flange that is upwardly bent and inwardly rebent and formed with a sloping shoulder, the free edge of the shouldered portion extending inward over the body of the sheet; whereby said roof-sheet is adapted to have its ridge-end retained by a ridge-cap engaging the face of the aforesaid shoulder of the roof-sheet flanging and hooking freely over the aforesaid extended free edge of the roof-sheet flanging; substantially as specified.
6. In an outside metal car-roof, a ridge-cap of inverted channel form with outwardly extending and inwardly rebent flanges along each edge of the channel forming sloping shoulders above said flanges, the channel and its edge-flanges being adapted to overlie and engage the shouldered edge flanging along the ridge-end of roof-sheets on opposite sides of the ridge of the roof; substantially as specified.
7. In an outside metal car-roof, a corner-cap which is doubly shouldered, at different levels, and adapted to overlie and retain the mutually adjacent ends of seam-caps and shouldered ridge-caps at the ridge of the roof; substantially as specified.
8. In a metal car-roof, in combination: freely floating roof-sheets flanged along all of their four edges and having each of the flanges formed to interlock freely within a reversely formed flange of an adjacent roof-member; ridge-caps of inverted channel form with an outwardly extending and inwardly rebent channels along each edge of the channel, the channel being adapted to overlie and engage the faces of the aforesaid shoulders of the roof-sheet flanging, and the rebent edge-flanges of the channel being hooked freely over the aforesaid extended free edges of the roof-sheet flanging; whereby the ridge-cap retains the opposite roof-sheets from displacement toward the eaves of the roof and at the same time forming with the roof-sheet flanging an interlocking connection that permits free shifting of the sheets toward the ridge of the roof; substantially as specified.

wardly rebent flange along each edge of the channel, the channel and its edge-flanges being adapted to overlie and freely interlock with the flanges along the ridge-ends 5 of the roof-sheets; seam-caps provided with depending, rebent flanges adapted to interlock freely within the flanges along the sides of the roof-sheets; and retaining means for the eaves-ends of the roof-sheets, said retaining means being adapted to engage freely with the eaves-end flanging of the roof-sheets, to permit the free movement of said sheets toward and away from the ridge of the roof.

15 9. In a metal car-roof, in combination: roof-sheets disposed on opposite sides of the ridge of the roof and each having along its ridge-end a flange that is upwardly bent and inwardly rebent and shouldered, the 20 free edge of the shouldered portion extending inward over the body of the sheet; a ridge-cap of inverted channel form with outwardly extending and inwardly rebent flanges along each edge of the channel, the 25 channel being adapted to overlie and engage the faces of the foresaid shoulders of the roof-sheet flanging, and the rebent edge flanges of the channel being hooked freely over the aforesaid extended free edges of 30 the roof-sheet flanging; whereby the ridge-cap retains the opposite roof-sheets from

displacement toward the eaves of the roof and at the same time forms with the roof-sheet flanging an interlocking connection that permits free shifting of the sheets toward the ridge of the roof; and a supplementary lock-strip inserted under the ridge-cap and between the ridge-flanges of the opposite roof-sheets, additionally to secure the said flanges in their interlocking engagement with the ridge-cap and at the same time permit them freedom of movement within said ridge-cap; substantially as specified.

10. In a car-roof, a ridge-cap and roof-sheets having flanges adapted to engage with each other by sliding movement in direction transverse to the ridge-line, and a ridge-joint lock-bar consisting of a filler-piece adapted to be inserted between and 50 block the disengagement of the seams formed on either side of the ridge by the engagement of the ridge-cap flanges within the ridge-end flanges of the roof-sheets; substantially as specified.
